UNITED STATES PATENT OFFICE.

HARRY H. CULMER, OF CHICAGO, ILLINOIS.

APPARATUS FOR COKING COAL.

Application filed January 22, 1920. Serial No. 353,204.

My invention relates to improvements in apparatus for coking coal, and refers more particularly to an apparatus in which the coal in batches is continuously conveyed through the coking oven without breaking the bond of the coke.

Among its salient objects are to provide apparatus in which the coal is continuously fed into a coking oven and removed therefrom without breaking the bond of the product; to provide apparatus in which the coal is fed through the oven in small quantities which permits of a more uniform heating and produces a coke product having a very uniform texture; to provide apparatus which is economical in the amount of heat required and one which does away with the loading and unloading of the individual coke ovens.

20 In the drawings:

Figs. 1 and 1^a show a diagrammatic view of the coking apparatus.

Fig. 2 is a sectional end view of the interior of the coking oven.

25 Fig. 3 is a detail of the coal car showing means of transporting same through the oven.

Fig. 4 is a detail plan view of the driving sheave.

30 Fig. 5 is a side elevation of parts shown in Fig. 4.

This coking process consists in general in loading finely ground coal at charging station 1 into a number of cars 2, which travel upon a track 3, being carried along by uprights 4 clamped to an endless steel cable 5. The uprights 4 are fitted with small spool wheels 6, which run upon a track 7 laid below the track 3. These uprights are clamped to the cable 5 at intervals by any suitable means and are adapted to contact the lugs 8 in order to push the coal car 2 along its track.

45 The coal cars being carried along by the uprights 4, proceed down an incline into a liquid basin 9, which together with the insulating hood 10 serves as a seal for the coking oven 11. This insulated hood has an aperture 12 beneath the surface of the liquid contained in the basin 9, which is large enough for the coal car to pass under it. After passing through this aperture, the coal

cars rise up the inclined portion of the basin into the interior of the coking oven, which consists of a long tunnel-like structure. The 55 coal cars proceed, moving very slowly through this tunnel, being constantly heated by heating gases supplied to the oven by oil or gas burners or other suitable means.

At the opposite end of the oven is another 60 insulated hood 10^a identical to that shown at the entrance and sealing the oven at this end. A basin 9^a filled with liquid similar to that previously explained, furnishes a liquid seal for the distilled vapors and gases. The coal 65 cars pass through an aperture 12^a similar to aperture 12 in the insulated hood 10. The cars, after emerging from this basin are ready to be emptied and to facilitate this, the track 3 diverts from the course of the end- 70 less driving cable 5. After diverting the cars of coke, the driving cable proceeds around a grooved sheave 13, which is notched at 14 to accommodate the vertical uprights, which push the cars. The cable then proceeds back 75 over a similar course through another oven to the charging stand 1, where it passes around an idler sheave (not shown), identical to that just explained. I do not wish to limit myself to this particular elongated 80 form of oven as it may be more economical to make the oven in a more compact form as far as heating is concerned.

To return now to the details of the coal or coke cars, it will be appreciated that they 85 must be built to withstand a very high temperature and must be specially constructed of refractory materials. The body of the car consisting of two hinged upright sides 15 and end pieces 16 is constructed of carbon 90 rundum and is held together by cast iron fittings. The truck of the car 17 is also of cast iron and is mounted upon bearings 18, which are fluid-tight and packed with graphite. The purpose of the graphite packing is to 95 furnish a lubricant for the shaft 19 during its transit through the oven, as oil or similar substance would not withstand the high degree of heat to which the bearings are subjected. To the shafts 19 are fixed the 100 flanged wheels 20.

The heat for the ovens is supplied by burners 21, controlled by valves 21^a, which are mounted between the walls of the two

arched tunnel ways and are supplied with fuel through a supply pipe 22, controlled by valves 22^a, and with air through ducts 23, which is preheated by passing over the top of the oven. These ducts are regulated by dampers 24. Pilot lights 25 are situated close to the top of the burners and are kept lit at all times, both to facilitate the lighting of the burner and to relight a burner which has been extinguished. These burners are situated at frequent intervals along and between the oven chambers or tunnel ways at places which are most advantageous to the economical heating. The heating gases pass up through the ducts 26 in the lower part of which are arranged silica clay retort bricks or bricks of similar material which will withstand a very high temperature. These bricks are arranged at 27 in staggered relation, permitting the gases to pass therethrough, and at the same time, absorbing a great part of their heat. The gases then pass over the arch of the oven in the direction shown by the arrows and are expelled through flues 28. The spent gases from the flues are collected in a flue running longitudinally of the oven and pass up through the stack 29. The incoming fresh air which is supplied to the burners through the ducts 23 enters above the dampers 30. The inner walls 31 of the ovens are constructed of brick which will withstand a very high temperature such as brick made of silica, carbonium and clay, or the common type of silica clay retort brick. The outer two shell walls are constructed of silica brick or a firebrick that will withstand high temperature. An insulating substance shown at 34 may be put over the two arches to further economize the heat generated.

The power used in driving the cars through the oven is transmitted to the cable 5 by means of the drive sheave 13, which is fixedly mounted upon a vertical shaft 35. To this shaft is also fixed a gear 36 which meshes with a worm 37 mounted upon the horizontal shaft 38. This horizontal shaft is mounted in suitable bearings 39. To this shaft is also mounted a gear 40 which meshes with a pinion 41 mounted on a shaft 42. The shaft 42 is mounted in bearings 43 and is directly connected to any suitable source of power such as an engine or motor. An endless cable 5 passes around the driving sheave 13 at one end of the system and an idler sheave (not shown) at the opposite end of the furnace. The cable is driven at a very slow speed in order that the coal will be completely coked in its travel through the oven.

At either end of the oven, in the basins 9 and 9^a, is contained a liquid seal which may be either oil tar or water. The two basins are connected by a trough running the length 65 of the oven and in which is set the tracks 7

upon which the small spool rollers 6 ride, which carry the uprights 4. The greater part of these uprights which are attached to the cable 5 are immersed in the liquid throughout their travel through the oven. 70 This liquid, besides serving as a seal for the gases in the oven, provides a cooling agent for the cable and the journals of the lower spool 6. A tar tank 44 with a draw-off pipe 45 from the interior of the oven 75 serves as a means for collecting the tars or other by-products from the coal. The tar from the tank may be drawn off through an outlet pipe 46.

This process of coking the coal is continuous in that the coal is loaded into cars at a loading station the cars then being grasped by uprights arranged at intervals on the cable, which are attached to an endless cable and are drawn through the coking oven, the heat in which ranges from 750° to 1800° F. The cable drawing the cars moves very slowly, giving ample time for the coke within the cars to be completely treated by the time it emerges from the opposite end of 90 the oven. Before the cable passes around the sheave, which returns the cable back into the oven, the car with the coke therein is diverted onto a track extension shown at 47 in Fig. 4. The coke may then be dumped from the cars which are then ready to be returned to be again sent with a fresh charge of coal through the oven. At this point a car of fresh coal may be inserted between the uprights to be taken back through the 100 oven. In this way, the cable carries a coking charge in both directions through the oven.

I claim as my invention:

1. In an apparatus for coking coal, the combination with an oven, a liquid seal at the entrance and exit of said oven, means for moving bulk charges of coal through said oven including engaging elements adapted to engage a movable container of coal and cause said container to travel through the oven, means at the exit of the oven for diverting said container to a point where the coke is discharged. 105

2. In an apparatus for coking coal, the combination with a coking oven having a liquid seal at either end, of means for heating said oven, means for conveying coal containers carrying the coal through the coking oven including means adapted to positively engage the containers and cause them to be moved through the oven. 115

3. An apparatus for coking coal, comprising an elongated oven, means for heating the same to a coking temperature, a liquid seal at the entrance to said oven, a liquid seal at the exit thereof, an endless conveyor passing through said oven, means carried by said conveyor for engaging a container and for slowly moving said container through 125 130

the coking oven, and means for diverting said container after passage through the oven, to a point of discharge.

4. In an apparatus for coking coal, the combination with a coking oven having a liquid seal at either end, of means for heating the oven, means for conveying coal con-

tainers carrying the coal through the coking oven, including means adapted to positively engage the containers and cause them to be moved through the oven, and means for collecting the by-products. 10

HARRY H. CULMER.
